UNITED STATES PATENT OFFICE.

JAMES H. RAND, JR., OF BUFFALO, NEW YORK, ASSIGNOR, BY MESNE ASSIGNMENTS, TO REMINGTON RAND INC., OF NEW YORK, N. Y., A CORPORATION OF DELAWARE.

FILING DEVICE.

Application filed June 11, 1926. Serial No. 115,274.

This invention relates to filing devices in which a plurality of horizontal bars support a series of pockets for the reception of reference data, these bars being arranged 5 to slide away from and toward each other for opening and closing the pockets.

In devices of the class described, it has commonly been the practice to form the pockets of a continuous strip of material, 10 simply folded over the supporting bars in a successive series of index pockets. The difficulty with this construction, however, is that in operation two adjacent support bars may be suddenly moved apart with too 15 fast a motion, so that as a result the papers or correspondence contained in that particular pocket are moved upwardly and thrown out of the pocket, and become disarranged. Also, with this type of independent pocket, the bottom of the pocket is apt 20 to bulge when the pocket is filled with papers of a very flexible nature, with the result that the papers assume a semi-cylindrical shape, crowded up in the bottom of 25 the pocket and in no condition for convenient reference.

An object of this invention is to provide a filing device of the class described in which the pockets are not independent but each 30 pocket has a common dividing wall with the adjacent pocket, and the bottoms of the dividing walls are secured to a longitudinal strip of material.

Another object of the invention is to provide 35 an improved filing device in which the separation of supporting bars is limited positively by chains or other devices.

A still further object of the invention is to provide pockets secured at the bottom 40 to prevent bulging when flexible papers are inserted therein; also to improve filing devices in other respects hereinafter specified and claimed.

Reference is to be had to the accompanying 45 drawings forming a part of this specification, in which,

Fig. 1 is a perspective view of my improved filing device.

Fig. 2 is a plan fragmentary view of 50 one end of the filing device.

Fig. 3 is a transverse sectional view through the filing device.

Fig. 4 is a longitudinal sectional view 55 through one end portion of the filing device.

Fig. 5 is a longitudinal sectional detail on a large scale showing one of the pockets and support bars.

Fig. 6 is an elevation of one of the support bars.

Referring to the drawings by numerals, 60 10 indicates a box or container having side walls 11 and end walls 12. These walls are composed of an outer shell and an inner lining 13 adapted to form an air space 14 65 therebetween. This air space is for the purpose of insulating the filing device in case of fire, the top of same being filled with any other kind of insulating material if desired. A pair of parallel slide bars 15 are 70 secured in a substantially horizontal position in the box 10 in any suitable way such as by passing through the end walls 12 and being threaded on their outer ends to receive nuts 16. In this way the slide bars 75 15 may be removed by axial displacement so as to remove or insert pockets.

The slide bars 15 support a plurality or series of support bars 17, having a loop or eye 18 at each end for slidably receiving 80 said slide bars. These support bars are preferably attached one to another at their ends by chains 19 so that the distance that they may be separated on the slide bars 15 is limited.

Arranged somewhat above the bottom of 85 the box 10 is a horizontally disposed strip of material 21, this material being preferably of a flexible nature such as cloth, cardboard, or the like. A pocket separator 22 90 is suspended from each of the support bars 17, the upper end of said separator being folded over the support bar and the loose end secured to the separator by any suitable means such as stitches 23, staples, or the like. 95 The bottom of each pocket separator 22 has a horizontally disposed flap or fold 24 adapted to abut against the strip of material 21 and be secured thereto by stitches 25, staples, or the like.

100 In this way papers 26 may be inserted in the space between the separator walls 22, and the pockets thus formed are prevented from bulging at the bottom, due to the fact that the bottom of the separator wall 22 is 105 secured to the strip of material 21. The pocket is also prevented from being unduly opened at the top by the chains 19 which limit the separation of the support bars 17. In order to facilitate reference to the data 110

or correspondence 26 contained in the pockets, a label holder 27 is preferably secured to each of the support bars 17, said label holder being preferably of a transparent material such as celluloid, so that a label 28 containing index characters may be slipped between folds thereof, and be readily visible through the upper transparent fold. This label holder is preferably disposed about 10 perpendicular to the line of vision.

I would state in conclusion that while the illustrated examples constitute a practical embodiment of my invention, I do not limit myself precisely to the details herein illustrated, and described, since manifestly the same can be considerably varied without departing from the spirit of the invention as defined in the appended claims.

What is claimed as new is:

- 20 1. A filing device, comprising a tray, a bottom strip member in said tray, a plurality of separator members having corresponding ends secured to said bottom strip member in spaced relation, and means carried by the tray supporting the opposite ends of said separator members for relative movement, said bottom strip member retaining said separator members in spaced pocket-defining relation and preventing deformation of the pockets.
- 25 2. A filing device, comprising a tray, a bottom strip member therein, a plurality of separator members having corresponding ends secured to said bottom strip member in spaced relation with each other and with the end separator members spaced similarly from the ends of the tray, and means carried by the tray engaging said separator members at the free ends and supporting

said members for relative movement, said means also supporting said separator members with the bottom strip spaced above the bottom of said tray, and said bottom strip retaining said separator members in spaced pocket-defining relation with each other and 45 the ends of said tray.

3. A filing device, comprising a tray, an inner lining in said tray mounted in spaced parallel relation to the side and end walls of the tray and forming a closed insulating chamber around the sides and end thereof, a bottom strip member in the bottom portion of the tray, a plurality of separator members having corresponding ends secured to said bottom strip member in spaced relation 50 relative to each other and the inner lining at the ends of the tray, and supporting means carried by the tray mounting the upper ends of said separator members for limited relative movement and supporting said separator members with the bottom strip member spaced above the bottom of the tray in substantially parallel relation, said bottom strip member retaining said separator members in pocket-defining relation with each other and 55 the ends of the tray.

4. A filing device, comprising a series of support bars mounted for sliding movement in a substantially horizontal plane, a strip member mounted in spaced parallel relation 70 to said bars, a plurality of separator strip members secured at corresponding ends to said strip member and at the opposite ends to said support bars adapted to form a series of pockets for cards and the like, and 75 connecting means between said support bars adapted to limit the separation of said bars.
